UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

COMPRESSOR.

Application filed April 26, 1926. Serial No 104,745.

This invention relates to compressors, and more particularly to unloading systems for compressors.

In many compressor installations it is found that intermittent driving of the compressor best meets the compressed fluid demand and in such installations it is customary to provide a compressor with an automatically controlled driving motor which begins to drive the compressor when the pressure of the compressed fluid falls to a predetermined minimum and which stops and so discontinues compressor drive when a somewhat higher predetermined desired maximum pressure is obtained. In such systems it is desirable to have the compressor started unloaded and in the case of compound compressors it obviously is best that the high as well as the low pressure cylinder be unloaded.

Among the objects of the present invention is the provision of improved unloading mechanism for a compound compressor. Another object is to provide improved unloading means controlled by the lubricating system of the compressor. A more specific object is to provide improved unloading means for a compound compressor which will automatically unload each stage thereof during starting and while coming substantially up to speed. Other objects and advantages of the invention will subsequently appear.

In the accompanying drawings, in which for purposes of illustration one embodiment which the invention may assume in practice is shown:

Fig. 1 is a side elevation of a compressor equipped with the illustrative embodiment of my invention.

Fig. 2 is an end elevation of such a compressor with certain parts shown in vertical section on the line 2—2 of Fig. 1.

Fig. 3 is an enlarged detail vertical sectional view through a portion of the high pressure cylinder unloading mechanism.

Fig. 4 is an enlarged detail sectional view of a check valve construction.

Fig. 5 is a section on the line 5—5 of Fig. 3.

While the invention may obviously be

embodied in other systems and with other types of pumping apparatus, it is shown herein embodied in an angle compound compressor system. In this system a compressor 1 comprises a low pressure cylinder 2 and a high pressure cylinder 3. The low pressure cylinder discharges through a connection 4 into an intercooler 5. The intercooler 5 is connected to the suction side of the high pressure cylinder 3 through a line 6. The crank shaft 7 of the compressor may be driven in any suitable manner.

Connected to the crank shaft 7 by a link 8 is an oil pump 9 whose suction side is connected to the crank pit or oil sump of the compressor 1. The pump 9 discharges oil through a check valve 10 to a line 11. The line 11 branches at a T 12 and one branch 13 leads to high pressure cylinder unloading mechanism later described. Another branch 14 leads into the cross 15 to whose lower arm 16 is connected. The upper arm of the cross 15 is connected through a special check valve 17 to a stand pipe 18 of well known construction, and suitable lubricant supply connections, not shown, lead off from this stand pipe. An excess supply of oil to the stand pipe is returned to the sump through a concentric overflow line 19. The fourth branch of the cross 15 receives a line 20 which opens through a manually controllable stop valve 21 into a T 22 whose lower branch is closed by a plug 23 which may be removed for drainage purposes as later described. The upper branch of the T 22 connects through a pipe 23a with the lower ends of a pair of parallel spaced cylinders 24. The cylinders 24 are mounted upon the cover of an intake closure type unloading valve 25 which cooperates with ports 26 to close the intake and thereby unload the compressor. Within the cylinders 24 are pistons 27 having vertically extending piston rods 28 connected by a cross arm or yoke 29. A stem 30 carried by the yoke 29 supports a weight 31 movable between the cylinders 24 and resting upon a nut 33. Below the nut 33 a second nut 35 is mounted and the portion of the rod 30 between the nuts

passes through an opening 36 in the middle of the valve 25, the nuts 33 and 35 being spaced by a somewhat greater distance than the length of the opening 36 in the valve 25 for a reason which will subsequently appear. The connection between the pipe 23^a and the cylinders 24 may assume various forms, but in all cases the pressures in the cylinders will be desirably equalized. The 10 spaces above the pistons 27 are connected by a cross channel to which is connected a pipe 38 which conducts any oil which may leak past the pistons into the frame where it flows to the crank pit.

15 The check valve 17 comprises a casing 40 divided by a septum 41 into chambers 42 and 43 respectively connected to the cross 15 and to the stand pipe 18. The septum is traversed by an opening 44 with which the valve 45 20 cooperates. A spring 46 normally maintains the valve closed and may be subjected to adjustable pressure if desired. A set screw 47 held in different adjusted positions by a lock nut 48 prevents the complete closure of 25 the valve 45 and accordingly permits leakage of oil through the check valve when the pump is not running.

The spring loaded check valve 17 is interposed between the oil pump 9 and the stand 30 pipe 18 in order to create sufficient pressure to overcome the weight of the low pressure unloading valve 25, weight 31, and attached parts. By adjusting the set screw 47 the valve 45 is raised from its seat as explained above, leaving a small opening through which oil from the cylinders 24 will escape into the stand pipe 18 when the compressor stops and the oil pump is not working. The weight 31 is therefore made heavy enough to overcome 35 the head of oil in the stand pipe 18 and bring the pistons in cylinders 24 to the bottom. The structure so far described is in many particulars similar to the unloading mechanism described and claimed in the copending 40 application of Wade H. Wineiman, Serial No. 259,788, filed October 26, 1918, which issued as Patent 1,602,791, on Oct. 12, 1926, but in certain details differs from that mechanism. The mode of operation of the low 45 pressure unloading mechanism may be briefly described before taking up the structure of the high pressure cylinder unloading mechanism.

Assuming that the compressor is starting, 50 the oil pump will deliver oil in increasing quantities as the compressor driving motor gains speed. The pressure of the spring 46 on the check valve 45 is adjusted so that the oil will not pass freely into the stand pipe 18 until the pressure of the oil in line 20 is sufficient to raise the pistons 27. It may take 55 from ten to fifteen seconds for the motor to reach full or pull in speed (the preferable speed for putting the load on the motor), and 60 the proportioning of the parts, and the

amount of leakage past the check valve 45 is sufficient so that the upward movement of the pistons 27 does not bring the lower nut 35 into contact with the valve 25 and unseat the latter until after the driving motor reaches its normal speed. This proportioning of the parts is obviously governed by the displacement volume of the two cylinders 24 and of the pistons, allowance being made for leakage past the check valve 45 and the pistons. As synchronous speed is reached in the case of a synchronous electric driving motor or the normal running speed in the case of an internal combustion engine, or other types of electric motors, the volume of oil pumped 70 will be increased owing to the increased speed of the pump and the unloading valve 25 will be promptly raised from its seat and held wide open as long as the compressor is running. After shut down, the valve will be 75 closed by the weight 31 in addition to its own weight and the weight of the pistons; and the oil in the cylinders 24 will be drained back through the slight opening past the check valve 45. By means of the stop cock 21 the oil may be shut off from the cylinders 24 and the oil drained off by the removal of the plug 23 in the T 22 when it is desired to examine 80 or adjust the low pressure cylinder intake closure mechanism.

For the purpose of venting the intercooler and avoiding the necessity for starting the compressor against substantially full load in the high pressure cylinder the opposite ends of the high pressure cylinder are provided 90 with check valves 51 and 52 which may be of any suitable form, but are herein shown as ball check valves connected by short pipe sections 53 with the clearance volumes at either end of the high pressure cylinders. Each of 100 the valves 51 and 52 comprises a casing 54 whose interior is divided into two chambers by a septum 55, the septum being traversed by an opening 56 upon which a ball check valve 57 seats. The bottoms of the valve casings 54 are provided with openings 58 through which stems 58^a extend into a position to engage with the check valves 57 and unseat the latter. During the loaded running 110 of the compressor the upper ends of the stems 58^a are spaced a short distance below the valves 57 to insure the complete closure of the latter. The two stems are joined together by a yoke 59 having arms 60 arranged at opposite sides of the lower check valve device 120 52. Any suitable means may be provided to permit relative adjustment of the stems 58^a. For example, the stem 58^a of the upper valve may be held by adjustable nuts 61 to the upper end of the yoke 59 while adjusting mechanism 62 may be arranged to cooperate with the stem 58^a of the lower valve. The yoke 59 is pivotally connected at 63 to a lever 64 which is mounted upon a link 65 and connected 125 at 66 to a vertically reciprocable rod 67 130

which engages at its lower end a head 68 resting upon a suitable flexible diaphragm 69. The diaphragm 69 forms the upper bounding wall of a chamber 70 formed in the casing 71 and the chamber 70 communicates through an opening 72 with the pipe 13, previously described. A spring 73 normally acts to hold the lever arm 64 in a position to raise the valve stems 58^a and accordingly to hold the check valves 57 off their seats. By reason of the connections described, the lower part of the diaphragm chamber 70 is subjected to the same pressure variations as occur in the cylinders 24.

15 The mode of operation of this portion of the mechanism may now be briefly noted. When the compressor has been idle for some time there will be no pressure underneath the diaphragm 69 and the spring 73 will therefore cause opening of the check valves 51 and 52, allowing the confined air to escape. These valves will remain open until, after the starting of the compressor, a sufficient oil pressure is built up in the chamber 70 to overcome the tension of the spring 73 and move the lever 64 upward to a sufficient extent to permit seating of the check valves 57. The parts are proportioned so that when the low pressure unloading valve is about to open, the pressure beneath the diaphragm 69 will overcome the spring tension and allow the check valves to close.

From what has been said it will be obvious that my improved compressor unloading system provides for the simultaneous loading of the high and low pressure cylinders and does not require any manual unloading of the high pressure cylinder or permit the imposition upon the compressor driving motor while the latter is coming up to speed of the burden of pumping the intercooler pressure into the discharge line against the pressure in the latter. The check valves 51 and 52 may obviously be arranged in different places either in the intake connection of the high pressure cylinder or in the discharge lines and may be controlled if desired automatically in other methods and by different mechanisms from those described.

50 While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

60 1. In a compressor system comprising a multi-stage compressor, unloading means for a low pressure stage, unloading means for a high pressure stage, a lubricating system, and means connected to the lubricating system for controlling said unloading means, said sec-

ond mentioned unloading means including a plurality of relief means and a unitary actuator for said relief means.

2. In a compressor system comprising a multi-stage compressor, unloading means for a low pressure stage, unloading means for a high pressure stage, a lubricating system including means for effecting lubricant flow under pressure, and means connected to the lubricating system for controlling said unloading system, said second mentioned unloading means including a plurality of vent means and a single means responsive to the pressure in said lubricating system for actuating said plurality of vent means.

3. In a multi-stage compressor the combination comprising a normally closed valve controlling the intake to one stage of compression, cylinder relief means for another stage of compression, and means for controlling said intake controlling valve and cylinder relief means comprising means, other than the multi-stage compressor, for generating a fluid pressure.

4. In a multi-stage compressor, the combination comprising a normally closed valve controlling the intake to one stage of compression, cylinder relief means for another stage of compression, and means for controlling said intake controlling valve and cylinder relief means comprising means, other than the multi-stage compressor, for generating a fluid pressure and for permitting said pressure to fall when said pressure generating means ceases to function.

5. In a multi-stage compressor, the combination comprising normally closed valve means for controlling the intake to one stage of compression, and cylinder relief valve means for another stage of compression, fluid pressure means for opening said first mentioned valve means and permitting said second mentioned valve means to close, and means including a non-seating, constantly partially open valve for controlling said fluid pressure and for permitting said second mentioned valve means to close.

6. In a multi-stage compressor, the combination comprising a lubricating system, means for producing lubricant flow therein under pressure, a valve means adapted upon opening to load or upon closing to unload one stage of said compressor, a valve means adapted upon closing to load or upon opening to unload another stage of said compressor, and means governed and operated by the lubricant pressure for moving both of said valve means.

7. In a compressor system, in combination, driving means, a compound compressor driven thereby, an intake unloader for said compressor, unloading means for a stage above the first fluid pressure motor means controlling said unloading devices, and liquid pressure generating means supplying

pressure to said motor means and driven by said driving means, said motor means being of the expandible chamber type and comprising relatively movable chamber forming elements a predetermined relative movement of which controls loading movements of said unloading mechanisms, the increase in volume in said motor means dur-

ing such relative movement bearing a pre-determined relation to the capacity of the liquid pressure generating means during the time required for said driving means to bring said compressor up to speed. 10

In testimony whereof I affix my signature.

HALBERT B. HALVORSEN.

CERTIFICATE OF CORRECTION.

Patent No. 1,692,268.

Granted November 20, 1928, to

HALBERT B. HALVORSEN.

It is hereby certified that error appears in the printed specification of the above numbered patent requiring correction as follows: Page 2, line 54, for the word "in" read "is"; page 3, line 81, claim 3, after the word "compressor" insert a comma, and line 128, claim 7, after the word "first" insert a comma; and that the said Letters Patent should be read with these corrections therein that the same may conform to the record of the case in the Patent Office.

Signed and sealed this 19th day of February, A. D. 1929.

(Seal)
